Primary Examiner—Doris V. Coles*Assistant Examiner*—Stacia Cadmus*Attorney, Agent, or Firm*—Evenson, McKeown, Edwards & Lenahan, P.L.L.C.[57] **CLAIM**

The ornamental design for a front face of a vehicle wheel, as shown and described.

DESCRIPTION

FIG. 1 is a front view of a front face of a vehicle wheel according to my novel design; and,

FIG. 2 is a perspective view from the front side of a front face of a vehicle wheel according to my novel design. The dash line included depicts environment and is not part of the claimed design.
